UNITED STATES PATENT OFFICE.

EMMETT W. STULL, OF WILKINSBURG, PENNSYLVANIA, ASSIGNOR, BY MESNE ASSIGNMENTS, TO ALLIS-CHALMERS MANUFACTURING COMPANY, A CORPORATION OF DELAWARE.

ELECTRICAL CONTROL SYSTEM.

1,160,092.

Specification of Letters Patent.

Patented Nov. 9, 1915.

Original application filed May 29, 1911, Serial No. 630,150. Divided and this application filed November 16, 1912. Serial No. 731,886.

To all whom it may concern:

Be it known that I, EMMETT W. STULL, a citizen of the United States, residing at Wilkinsburg, in the county of Allegheny and 5 State of Pennsylvania, have invented a certain new and useful Improvement in Electrical Control Systems, of which the following is a specification.

This invention relates to electrical control 10 systems, especially to such systems as are intended for operation from separate sources of different potential.

For reasons of economy, it has been found 15 desirable to use higher voltages for the operation of interurban electric railways than are permissible for the ordinary city railways. The common voltage used in cities is about 600. By using double that voltage, or 20 1200 volts, for interurban service, a great saving in copper or in the number of substations may be effected. Since most interurban cars are also used more or less for city service, it becomes necessary in most cases 25 to arrange the electrical apparatus on the cars which are used on such higher voltage interurban systems so that they may be used on the lower voltage city systems. It is the primary object of this invention to provide such an arrangement.

30 In Patent No. 1,050,497, granted to applicant Jan. 14, 1913, on an application, of which this application is a division, there is described a control system as applied to the operation of the motors and auxiliary apparatus on a car of an electric railway system, whereby the car can be efficiently operated on sections of the line supplied at different potentials. In the preferred form 35 of my invention in said patent, which relates to the control of the motors, the same voltage per motor on the high and low voltage sections of the line is obtained by connecting the motors in series for the high voltage interurban service and connecting 40 them in parallel for the low voltage city service, the ordinary control of the motors being effected by connecting the motors in groups and by putting the groups in series 45 and parallel relation, while the proper connections for the high and low voltage parts 50 of the line are obtained by putting the motors in each group in series and parallel relation. The operation of the system described further includes the use and proper

connection of resistance elements in the motor circuits and means for effecting the various changes in the operating connections, along with special safeguards for preventing the use of a set of connections unsuitable for the supplied circuit. 55

The present invention is more particularly related to the auxiliary apparatus used upon the cars. Certain auxiliary apparatus requires a supply of fairly constant voltage, and in order to operate this auxiliary apparatus on both the higher and lower voltage sections of the line, there are provided suitable arrangements whereby practically the same voltage is always supplied to the auxiliary apparatus. Thus various lighting 60 circuits are connected in series and parallel according as the higher or lower voltage is supplied; and other circuits, such as the air-compressor-motor circuit, the headlight circuit, and the control circuits, have resistances connected in them for the higher voltage supplied, such resistances being short circuited when the lower voltage is supplied. The connections for the auxiliary apparatus are preferably changed by the 65 same switch which changes the connections of the parts of the resistance sections, this switch, while in the particular system described being of the hand operated type, 70 may be operated in any suitable manner. 75

The various novel features of the invention will appear from the description and drawings, and will be particularly pointed out in the claims.

Figure 1 is a diagram showing the connections for one car in a system embodying the invention; Fig. 2 is a side view of the combined series-parallel and reversing switch in the forward high voltage position; Fig. 3 is an end view of the connection-changing 90 mechanism of such switch, with the switch in the same position; Figs. 4 and 5 are sections on the lines 16-16 and 17-17 of Fig. 2, Fig. 5 showing the reversing mechanism for the switch; and Figs. 6, 7, and 8 are 95 views corresponding to Figs. 3, 4, and 5, but with the switch in the backward high voltage position.

The trolley wire or third rail has high and low voltage sections 22 and 23 respectively. 100 The current from either section may be supplied to the car through a trolley or collector 24. Each car may be operated separately,

or there may be a number of cars controlled in common and operated together in a train. On each car there are four motors, A, B, C, and D, which are arranged in two groups, 5 A and B, and C and D. The two motors forming a group are connected in series for high voltage and in parallel for low voltage. These connections are obtained by a combined series-parallel and reversing switch 10 25, which also reverses the relative direction of current through the field windings and armatures of such motors to obtain the desired direction of movement of the car; this switch will be considered in detail herein-after. The speed of the motors is controlled by a group of solenoid-operated switches 26 to 36 inclusive. The operating solenoids for these switches are controlled, through suitable train wires *a, b, c, o*, by 15 20 the master controlling switch 37, and the switches are operated to control the groups of motors practically in accordance with the modified "Bridge" control scheme shown in Patent No. 1,017,270, granted to applicant 25 Feb. 13, 1912, five resistance sections 38 to 42 inclusive being used. The resistance section 40 is for use in the bridge wire, and may sometimes be omitted. The other resistance sections are for use in the legs of the 30 bridge, and are each divided into two parts. The resistance sections 40 may also be so divided, if desired. The parts of the different resistance sections may be connected in series and parallel by the drum switch 43, 35 which is preferably operated by the same handle 44 which is used for operating the master reversing switch 45 and the master connection switch 46.

The combined series-parallel and reversing switch 25 is of the drum type and has 40 four positions, forward high voltage (F H), forward low voltage (F L), backward high voltage (B H), and backward low voltage (B L), arranged in the order named. This 45 order may be changed as desired provided the two positions most remote from each other produce both different directions of movement and different interconnections of the motors. There is the same distance between the first and second positions named 50 as between the third and fourth. The distance between the second and third positions may be the same as that between the other pairs of adjacent positions, or different: it is shown as the same. In either case the distance between the first and third positions is the same as that between the second and fourth. The contacts for the two groups of motors, A and B, and C and D, 55 are preferably arranged on opposite sides of the controller drum, as illustrated in Figs. 4 and 7, though they may all be arranged on the same side of the drum in a manner similar to that which for simplicity of diagram 60 is shown in Fig. 1. The direction-control-

ling mechanism is shown at the left hand end of Fig. 2 and in Figs. 3 and 6, and the connection-controlling mechanism at the right hand end of Fig. 2 and in Figs. 5 and 8.

The direction control is obtained by two solenoids 54 and 55, which are energized by the master reversing switch 45 in the two operating or setting positions of the latter. These two solenoids when energized move a bar 56, loosely mounted on the shaft 57 of the drum 25, to the positions shown in Figs. 3 and 6 respectively. In such movement one or the other of the pawls 58 and 59 carried by said bar engages a notch in a disk 60, fast on the shaft 57, and moves the drum 25 through an angle equal to that between either forward position and the corresponding backward position; in other words, it moves the drum through an angular distance equal to twice that between two adjacent rows of contacts thereon. Each pawl 58 and 59 may cooperate with either one of two notches, the angular distance between such two notches being equal to that between two adjacent rows of contacts on the drum 25. The pawls 58 and 59 are so mounted that they are automatically disengaged from the notches of the disk 60 upon the de-energization of the solenoids 54 and 55 respectively. A spring-pressed pawl 51 maintains the bar 56 in either of its positions.

The connection control is obtained by two solenoids 62 and 63, which are energized by the master connection switch 46 in the two operating or setting positions of the latter. These two solenoids when energized respectively move a bar 64, loosely mounted on the shaft 57, to the position shown in Fig. 5 and a position an equal distance on the other side of the horizontal from that shown in such figure. In such movement one or the other of the pawls 65 and 66 carried by said bar engages a notch in a disk 67, fast on the shaft 57, and moves the drum 25 through an angle equal to that between either high voltage or series position and the corresponding low voltage or parallel position: in other words, it moves the drum through an angular distance equal to that between two adjacent rows of contacts thereon. Each pawl 65 and 66 may cooperate with either one of two notches, the angular distance between such two notches being equal to twice that between two adjacent rows of contacts on the drum 25. The pawls 65 and 66 are so mounted that they are automatically disengaged from the notches of the disk 67 upon the de-energization of the solenoids 62 and 63 respectively. A spring-pressed pawl 67 maintains the bar 64 in either of its positions.

By this arrangement the direction solenoids may move the drum 25 from either the high or low voltage forward position to

the corresponding backward position or vice versa, and the connection solenoids may move it from either the forward or backward high voltage position to the corresponding low voltage position or vice versa. The distance between the two notches with which each of the pawls 58 and 59 co-operates is equal to the distance through which the connection solenoids may move the drum, while that between the two notches with which each of the pawls 65 and 66 co-operates is equal to that through which the direction solenoids may move it.

The master control switch 37, the master reversing switch 45, and the master connection switch 46 are preferably mounted in the same controller box. There may be two similar master controllers on a car, the second being indicated in outline in Fig. 1 at 68^a. The master control switch 37 has eight operating positions, in addition to a transition or "Bridge" position T and an off position O. The master reversing switch preferably has five positions, FS, FI, M, BI, BS, the two end ones being the operating or setting positions. The two positions adjacent to the middle position make no connections but are merely indicating positions to indicate to which position the master reversing switch was last moved. By providing these two positions, the current for the direction solenoids 54 and 55 may be cut off as soon as such solenoids have completed their work. If desired, suitable provision may be made for biasing the master reversing switch from the two setting to the two indicating positions, as in the manner shown in Patent No. 916,898, granted to applicant March 30, 1909. The master connecting switch 46 is made in the same general manner, but with four positions, HS, HI, LI, LS; it admits current to the connection solenoids 62 and 63 only when it is in its extreme or setting positions, the two intermediate positions being for indicating purposes.

Suitable operating and interlocking mechanism may be provided for the switches 25, 37, 43, 45 and 46 to insure proper operation thereof, as described in applicant's Patent No. 1,050,497, granted Jan. 14, 1918.

In the controlling circuits is a circuit-breaker 82, biased to open position. When moved to closed position it is held there by a magnet 83, which becomes de-energized upon failure of voltage for any reason and allows the circuit-breaker to open. When open, the circuit-breaker is held in open position by a latch 84, which is not released until the magnet 83 is again energized; when the circuit-breaker may be closed by hand. The magnet 83 is in series with the operating solenoid of the main circuit-breaker 85, an overload switch 86, and the switch 87 and its operating solenoid. In shunt to the

switch 87 is the solenoid 88 of the double-throw switch 89. The solenoid of the switch 87 is so wound that when the trolley 24 is on a low voltage section of the line the switch 87 remains in its lower or closed position, thus short-circuiting the solenoid 88, and when the trolley 24 passes to a high voltage section the switch 87 is opened by its operating solenoid, thus throwing current through the solenoid 88 to raise the switch 89 from its lower to its upper position.

Between the high and low voltage sections of the line there is an insulated section 90, disconnected from both the high and low voltage sections. When the car is passing from either the high or the low voltage section to the other, it passes over this section 90, thus causing the de-energization of the coil 83 and the operating coil of the circuit-breaker 85. This causes the circuit-breakers 82 and 85 to open, thus disconnecting all circuits save that including the coil 83. If any of the various controlling switches are closed at this time, their operating solenoids are immediately de-energized and they are allowed to open, thus breaking all motor circuits. The insulated section 90 is paralleled by a short section 91, which is preferably connected to the low voltage section 23. The section 91 is for the purpose of allowing the energization of the various circuits on the car in case the car should stop with the trolley on the section 90.

The switch 43 in its high and low voltage positions respectively also puts two or more lighting circuits 47 and 48 in series and parallel, and cuts into and out of circuit resistance 49 in the circuit of the air compressor motor 50, resistance 51 in the circuit of the head-light 52, and resistance 53 in the control circuit. The lights and the air compressor may be otherwise controlled in any suitable or desired manner. Thus it can be seen that a means is provided for maintaining the lights of the car at full brilliancy whether the car is on a 600 volt or a 1200 volt section of the line; and likewise, for impressing a constant voltage on the terminals of the compressor pump and the operating magnets of the control circuits.

In explaining the operation of the system, it will be assumed for simplicity that there is but a single car. If several cars are coupled together to form a train, the operation of the apparatus would be the same on all the cars, suitable connections between the cars being made by the train wires *a*, *b*, *c*, *d*.

Assume that the car has been operating on the low voltage section 23. In order for it to operate the switch 89 is down, and the switches 43 and 25 are in low voltage position. If the car is going forward, the switch 25 is in its forward low voltage posi-

tion. When the trolley leaves the section 23 and engages the section 90, the various circuits are deenergized in the manner already described. When the trolley reaches the high voltage section 22, the circuit including the magnet 83 is energized, thus releasing the latch 84, closing the circuit-breaker 85, lifting the switch 87, and throwing current through the solenoid 88 to cause it to raise the switch 89. The lifting of the latch 84 permits the manual closing of the circuit-breaker 82. The closing of this circuit-breaker and the lifting of the switch 89 supplies the potential of the section 22 to the contact 92 on the switch 43.

The motorman now turns his master reversing switch 45 to its middle position M, transfers its handle 44 to the switch 43, and moves the latter from low voltage to high voltage position. This puts the parts of the resistance sections 38, 39, 41, and 42 in series, whereas before they were in parallel. It also connects the contacts 92 and 93, thus energizing the wire 94. This wire leads to the contact 95 on the switch 25; but since this switch is in low voltage position, with the contact 95 out of engagement with any of the contact segments on the drum of said switch, the circuit stops there. The wire 94 also leads, through a resistance 96, to a contact 97 on the master connection switch 46.

The handle 44 is now transferred to this switch to move it to high voltage setting position HS, and the connection is completed from the contact 97 through the train wire b to the solenoid 63. The solenoid 63, being thus energized, moves the drum 25 from the forward low voltage position to the forward high voltage position, the latter being the one indicated in Figs. 2 to 5 inclusive.

The movement of the switch 25 to the high voltage position completes the circuit 45 from the contact 95 to the wire 98, which is suitably connected to the motor 50 of the air compressor, the headlight 52, the lamp circuits 47 and 48, and the control circuit supply wire 99. The switch 43 being in 50 high voltage position, the lamp circuits 47 and 48 are in series, and the resistances 49, 51, and 53 are in their associated circuits. The positions of the switches 43 and 25 must thus correspond in order that these various 55 circuits may be supplied. The switch 46 being now returned to high voltage indicating position, the handle 44 may be removed and placed on the reversing switch 45. The latter is then moved to forward indicating 60 position, assuming that the car is to continue in its forward direction of movement. If moved beyond such position to forward setting position no harm is done, for with the bar 56 in the position shown in Fig. 3, 65 the energization of the solenoid 54 produces

no results; such movement merely insures the setting of the switch 25 in a forward position and prevents the operation of the master control switch 37 until the master reverser is brought back to indicating position. The car may now be started by the operation of the master control switch 37, the movement of which to its successive positions connects the motor groups, each of which consists of two series connected motors, in series and parallel with the resistance sections, which are connected in two groups of two series connected sections, the various relative positions of the motors and resistances being illustrated, and specifically described in Patent No. 1,050,497, granted to applicant Jan. 14, 1913. In order to stop the car, the master control switch 37 is moved back to off position, changes in the connections taking place in an order substantially the reverse of those that take place in bringing the motors to the last running position.

In case of an overload at any time, the overload coil 100 lifts its core and closes the switch 86. This short-circuits the operating solenoid of the circuit-breaker 85, causing the opening of such circuit-breaker. This interrupts all motor circuits. Any arcing occurs at the circuit-breaker 85; this arcing may be suppressed in any suitable manner. The overload switch 86 is held in its closed position by the holding coil 103, which remains energized until the master control switch 37 is moved back to its off position. When this master switch is moved back to off position the holding coil 103 is deenergized and the switch 86 allowed to drop, thus again throwing current through the operating solenoid of the circuit-breaker 85.

When the car passes to a low voltage section 23, the switches 87 and 89 drop to their lower positions, thus connecting the contact 104 to the trolley. To complete the circuit 110 further, the switch 43 must be turned to low voltage position, thus putting the parts of each of the resistance sections 38, 39, 41, and 42, and also the two lamp circuits 47 and 48, in parallel instead of in series, and short-circuiting the resistances 49, 51, and 53. The movement of the switch 43 to low voltage position renders it possible for the solenoid 62 to be energized by the movement of the master connection switch 46 to low voltage position, the circuits for the connection magnets 62 and 63 being the only parts of the control circuits which are independent of the position of the switch 25. When the solenoid 62 has moved the switch 125 25 to a low voltage position, the connection for the remaining controlling circuits is completed through the proper contact on the switch 25 and the contacts 105 and 106, thus energizing the wires 98 and 99.

The control may now be effected in the same manner as that already described, the only difference being that the two parts of each of the resistance sections 38, 39, 41, and 5 42, and the two motors of each group of motors are now in parallel instead of in series.

For backward movement of the car, the solenoid 55 is energized, by the proper 10 movement of the master reversing switch 45, to move the combined series-parallel and reversing drum 25 from a forward position, such as shown in Figs. 2 to 5 inclusive, to a backward position, such as shown in Figs. 15 6 to 8 inclusive. As illustrated, both of these positions are high voltage positions; but if the drum is already in a low voltage position, the energization of the solenoid 55 will move it to the other low voltage 20 position.

It sometimes happens that one or more of the motors becomes disabled. It is then desirable that the remaining motors, or some of them, be operable to bring the car to the 25 car barn. In the arrangement shown this can be done by means of the cut-out switches 101 and 102. By throwing the switch 101 from its upper or full line position to the lower or dotted line position, the motors 30 A and B are cut out, the remaining motors and all the resistance sections being left in circuit. The system may then be operated to control the motors C and D. The cut-out switches 101, 102, are provided with additional blades, respectively in parallel with each other in the wire 99, or the main supply wire for the control circuits. Thus when both cut-out switches are open, it is impossible to supply operating current to any of 40 the control circuits except to the solenoids 62 and 63. By the provision of these extra blades on the two cut-out switches, it becomes impossible to obtain a short circuit from trolley to ground, or a useless waste of 45 current even less than a short circuit, when either or both of the groups of motors are cut-out.

It can readily be seen that a system of auxiliary apparatus for the car is provided 50 which operates substantially as well on either high or low voltage sections of the line. When operating on high voltage, one group of lamps 47 or 48 is connected in series to the other so that each forms a series 55 resistance for the other which is cut-out of the particular circuit when operating at low voltage, in a similar manner as is the resistance 51 cut-out of the head-light circuit, the resistance 49 cut-out of the compressor circuit, or the resistance 53 cut-out of the control circuit.

It should be understood that it is not desired to be limited to the exact details of construction shown and described, for ob-

vious modifications will occur to a person skilled in the art.

It is claimed and desired to secure by Letters Patent,—

1. In an electric railway system, a line having high and low voltage sections, a motor operated car, auxiliary electrical apparatus, a resistance in the circuit of said auxiliary apparatus, means for cutting out said resistance when the car is on the low voltage section, and means for preventing the completion of the circuit of said auxiliary apparatus when the car is on a high voltage section unless said resistance is cut in. 75

2. In an electric railway system, a line having high and low voltage sections, a motor operated car, a plurality of lighting circuits for the car, means for putting said circuits in series when the car is on a high voltage section and in parallel when the car is on a low voltage section, and means for preventing the completion of said lighting circuits unless they are so connected. 85

3. In combination, a plurality of pieces of electrical apparatus, two sources of supply of different voltages, a circuit for each piece of electrical apparatus, a resistance for each circuit, and means requiring each piece of apparatus to be connected in series with its corresponding resistance when the apparatus is connected to the source of higher voltage. 95

4. In combination, a plurality of pieces of electrical apparatus, two sources of supply of different voltages, a circuit for each piece of electrical apparatus, a resistance for each circuit, and means requiring each resistance to be disconnected from the circuit of the corresponding piece of apparatus when the apparatus is connected to the source of lower voltage. 100

5. In combination, two sources of supply of different voltages, a plurality of pieces of electrical apparatus, a resistance for the circuit of each piece of electrical apparatus, and means for connecting each piece of electrical apparatus in series with its corresponding resistance when the car is connected to a high voltage section of the line and for disconnecting said resistances from their corresponding pieces of apparatus when the car is connected to a low voltage section of the line. 110

6. In a system of distribution, two sources of supply of different voltages, a plurality of lighting circuits, a resistance for each lighting circuit, means for putting the corresponding resistance in series with each lighting circuit when the lighting circuits are connected to the source of higher voltage and for disconnecting said resistance when the lighting circuits are connected to the source of lower voltage. 120

7. In a system of distribution, a source of

- high and low voltage, a plurality of lighting circuits, a resistance for each circuit, means for cutting out the resistance from each circuit when the system is connected to the 5 source of low voltage, and means for preventing the completion of said lighting circuits when the system is connected to the high voltage source unless said resistance is connected in circuit.
10. 8. In a system of distribution, a source of high and low voltage, a plurality of lighting circuits, a resistance for each circuit, means for connecting each lighting circuit in series with its respective resistance when the 15 system is connected to the source of high voltage, and means for preventing the completion of said lighting circuits when the system is connected to the source of low voltage unless said resistance is disconnected 20 from said lighting circuits.
9. In a lighting system, sources of high and low voltage, a plurality of lighting circuits, and means for connecting said circuits in series to the source of high voltage and 25 in parallel to the source of low voltage and means for preventing the completion of said circuits unless they are so connected.
10. In combination, two sources of supply of different voltages, two distributing 30 circuits, a double-acting switch adapted in one position to close one only of said circuits and in another position to close the other only of said circuits, an electro-magnet for operating said switch, and a second 35 switch for automatically short-circuiting the operating electro-magnet of the first switch, whereby one distributing circuit may be connected to the source of higher voltage and the other distributing circuit may be connected to the source of lower voltage.
40. 11. A distribution system adapted to be supplied with energy at different voltages and comprising a plurality of distribution circuits, means for connecting said distribution circuits in series when said system is supplied at a higher voltage and in parallel when said system is supplied at a lower voltage, and means for preventing the completion of said circuits unless they are so 45 connected.
50. 12. A system of electrical distribution
- adapted to be supplied with energy at varying voltage and comprising a plurality of distribution circuits, a resistance for each circuit, and means requiring each resistance 55 to be disconnected from its corresponding circuit when said system is supplied with energy at a lower voltage and requiring each resistance to be connected in circuit when said system is supplied with energy at 60 a higher voltage.
13. A system of electrical distribution adapted to be supplied with energy at different voltages and comprising a distribution circuit, a resistance adapted to be connected 65 in said circuit, means for connecting said resistance in and cutting it from said circuit, and means controlling the supply of energy to said circuit for insuring that said resistance is in circuit when said distribution circuit is supplied at a higher voltage 70 and is cut out when said distribution circuit is supplied at a lower voltage.
14. A system of electrical distribution adapted to be supplied with energy at different voltages and comprising a plurality of distribution circuits, means for connecting said circuits in series and in parallel, and means controlling the supply of energy to 75 said circuits and insuring that the circuits 80 are in series when the voltage of said system is of a higher value and in parallel when the voltage of said system is of a lower value.
15. A system of electrical distribution 85 adapted to be supplied with energy at different voltages and comprising a plurality of circuits, and automatically acting controlling means for insuring the completion of one only of said circuits when said system 90 is supplied with energy at one voltage and the completion of the other only of said circuits when said system is supplied with energy at a different voltage.

In testimony whereof, the signature of the 95 inventor is affixed hereto in the presence of two witnesses.
